UNITED STATES PATENT OFFICE.

FOREST V. DETWILER, OF CHICAGO, ILLINOIS.

REFRIGERATOR.

1,112,687.

Specification of Letters Patent.

Patented Oct. 6, 1914.

Application filed May 4, 1908. Serial No. 430,653.

To all whom it may concern:

Be it known that I, FOREST V. DETWILER, a citizen of the United States, residing at Chicago, in the county of Cook and State 5 of Illinois, have invented certain new and useful Improvements in Refrigerators, of which the following is a specification.

This invention relates to improvements in refrigerators and more particularly to 10 the construction thereof and the primary object of the invention is to provide an improved metallic refrigerator of sectional construction and one in which the sections may be all shaped or formed and then assembled to produce a refrigerator of any desired size.

A further object is to provide improved means for securing the various sections and parts together.

20 A further object is to provide an improved refrigerator which will be thoroughly insulated and improved means for holding and securing the insulation or packing in position whereby the insulation will 25 be prevented from settling which would produce an air space within the walls of the construction after the refrigerator has been completed.

A further object is to provide an improved 30 metallic refrigerator which will be simple, durable, cheap and light in construction and effective and efficient in operation.

To the attainment of these ends and the accomplishment of other new and useful 35 objects, as will appear, the invention consists in features of novelty in the construction, combination and arrangement of the several parts hereinafter more fully described and claimed and shown in the accompanying drawings, illustrating an embodiment of the invention and in which—

Figure 1 is a detail perspective view of a refrigerator of this character constructed in accordance with the principles of this invention. Fig. 2 is a sectional view on line 2—2 of Fig. 4. Fig. 3 is a sectional view on line 3—3 of Fig. 4. Fig. 4 is a sectional view on line 4—4 of Fig. 3. Fig. 5 is a detail perspective view of one of the lower 45 corner pieces or castings. Fig. 6 is a detail perspective view of the lower portion of

one of the metallic corner pieces. Fig. 7 is a detail perspective view of a portion of two of the sections of one of the sides showing the fastening means for securing these 55 sections together. Fig. 8 is a detail plan view partly in section of the frames for supporting the bottom and top of the refrigerator. Fig. 9 is a detail perspective view partly in section of two sections of 60 the top and bottom showing the manner of securing the sections together and the manner of holding the packing or insulation. Fig. 10 is an enlarged detail sectional view of one of the upper corners of the refrigerator. Fig. 11 is an enlarged detail sectional 65 view of the front of the refrigerator showing the stile between the upper and lower doors of the refrigerator. Fig. 12 is a detail perspective view of the rear corner 70 posts. Fig. 13 is an enlarged sectional view partly broken away of one of the rear corners with the parts assembled and showing the tie bolt for fastening the parts together. Fig. 14 is a detail perspective view of a portion 75 of the side showing the manner of securing the paneled sections together. Fig. 15 is a detail perspective view partly in section showing the manner of securing the cross stile in position.

80 Referring more particularly to the drawings and in the present exemplification of the invention, the numeral 20 designates one of the sections of which the top and bottom are composed. These sections may be constructed of any desired size and length and are each provided with side flanges 21, 22, the flange 21 being provided with a portion 23 bent back upon itself to form a lip, (see Fig. 9) and the other flange 22 is provided 85 with a straight edge, as shown, to fit into the lip 23 of the next adjacent section. One of the flanges, preferably the flange 21, is provided with a plurality of apertures 24 and the other flange 22 is provided with a 90 plurality of cut out portions to form ears or extensions 25 which are adapted to be inserted or passed through the apertures 24 in the adjacent flange of the next section and the extremities thereof are adapted to 95 be bent over or flanged down upon the face of the next adjacent flange 21 for securing 100

the sections together, and when so connected the walls will be provided with spaced inwardly projecting ribs. The flanges 21 are also preferably provided with cut out portions or ears 26 which are located preferably along the edge of the flange where it overlaps the flange of the next adjacent section and these ears or projections 26 are preferably pointed, as shown, for a purpose to be hereinafter more fully set forth. Any number of these sections 20 may be secured together to produce a top and bottom of the refrigerator of any desired size. When the desired number of sections have been thus secured together, the troughs formed by the flanges 21, 22, may be filled with suitable packing or insulation 27 and this packing or insulation, preferably comprises mineral wool W of any desired thickness, which is first placed into the troughs. Paper P may be then placed upon the wool and then flax fiber F may be arranged upon the paper and then another piece of paper P is arranged upon the fiber F. Upon this last layer P may be arranged another piece of mineral wool and this last layer of mineral wool should be of a thickness to substantially fill the troughs formed by the flanges 21, 22. When the entire top and bottom sections are filled with insulation in this manner another sheet of insulating material 28 may be provided and this insulation 28 preferably comprises flax fiber interposed between two sheets of paper and the three elements secured together in any desired or suitable manner, preferably by stitching the same. This insulation 28 may be then placed upon the top and bottom sections and over the insulation which has already been inserted therein and is secured in position by forcing the projecting ears 26 through the insulation, as shown more clearly in Fig. 9, and when the insulation is in proper position the extremities of these ears may be flanged down upon the top of the insulation for securely holding the filling material and this insulation in position. When the top and bottom sections have been thus formed they are each inserted into a frame 29, shown more clearly in Fig. 8 of the drawings. This frame is preferably of a channel formation with the channel portions facing each other so that the top and bottom sections may be respectively inserted within the frames through one side thereof, which is left open, and when the section is in position the extremities of the open side may be secured as at 30. The sections are preferably of a size slightly less than the frame 29 and interposed between the edges of the sections and the bottom of the channel portions of the frame and surrounding the frame is a filler 31 preferably in the form of a strip of wood or any other suitable material, as

shown more clearly in Fig. 10 of the drawings, and this filler is held from displacement preferably by means of fastening devices 32 which are driven through portions of the frame 29 and into the filler 31. When the bottom of the refrigerator is thus formed the lower corner pieces 33 may be secured thereto. These pieces 33, as shown more clearly in Fig. 5 of the drawings, are preferably in the form of a casting provided with a hollow base 34 into which is inserted a suitable filler block 34^a, and into which filler are inserted the extremities of the supporting casters 35. A portion of the casting 33 above the top, or flange 36 of the base is preferably of a right angle construction and projecting laterally from said portion and spaced above the flange 36 of the base and substantially parallel thereto is a flange 37 and this flange is located above the top of the base 36 a distance substantially equal to 85 the height of the frame 29 so that the extremities or corners of the frame may be inserted into the space between the flange 37 and the top 36 by which latter the bottom of the refrigerator is supported. When the corner pieces are thus attached to the frame, they may be secured against displacement in any desired or suitable manner, preferably by means of fastening devices, such as screws, bolts or the like 37 which pass through suitable apertures 38 in the flange 37 and through the adjacent portion of the frame 29 into the filler 31 within the frame, as shown more clearly in Fig. 13.

The sides of the refrigerator, designated generally by the reference numeral 39 in Fig. 1 of the drawings, are constructed of sections similar to the sections 20 with the exception that there may be provided in the side sections suitable panels 40. These sections are secured together in the same manner as the sections 20 and the insulation or filling 27 is inserted therein in the same manner and the insulation 28 is also secured and supported by the side sections by means of similar ears or projections 26. Any number of the side sections 20 may be secured together to produce a refrigerator of any desired height and when the sections are thus assembled they may be secured or held in position at the rear corners of the refrigerator by means of uprights or posts 41, 42, arranged at the rear corners of the refrigerator, as shown more clearly in Figs. 4 and 12 of the drawings. These uprights may be constructed of any suitable material such as wood or the like, and are of a height substantially equal to the height of the refrigerator above the base, and each of the uprights is provided on its outer face with a plurality of grooves or kerfs 43 which are spaced from each other so that when the sides are constructed the flanges 21, 22, at

the rear extremities hereof may be inserted within the respective kerf 43 and the kerfs are of such a length as to permit the extremity of each of the side sections to slightly 5 overlap the outer face of the upright, as shown more clearly in Fig. 4, and these parts may be held against displacement when thus assembled in any desired or suitable manner, preferably by means of fastening devices passing through suitable apertures 44 in the sections 20.

The back of the refrigerator, designated generally by the reference numeral 45 in Fig. 4 of the drawings, is constructed of sections 46, 47, shown more clearly in Figs. 7 and 14 of the drawings. The section 46 is of a U-shaped formation and is provided with slots or apertures 48 adjacent the extremities thereof and in each of the side walls at 20 a point in proximity to the bottom of the section. The section 47 is shaped to form a panel intermediate the sections 46 and is also of a substantially U-shaped formation. The extremities of the sides 49 of the panel 25 section are preferably bent back upon themselves as at 50, shown more clearly in Figs. 7 and 14, to form lips under which the extremities of the sides of the sections 46 are adapted to engage when the sections 46 and 30 47 are placed together. The extremities of the panel portion 47 are slotted as at 51 (see Fig. 7) and the ends of the panel portion intermediate the flanges 49 are offset as at 52 and deflected laterally as at 53 35 to form a flange which is spaced slightly above the body portion of the panel 47. The panel sections are slotted at 51 while the panel is being formed and before the side flanges 49 are shaped and during this 40 step of the formation of the panel portion the portion which forms the side flanges adjacent the extremities of the panel section are stamped or cut away as at 54 to form a projecting ear or extension 55, which is 45 adapted to project laterally beyond the outer face of the side flanges 49 when the extremity of the panel is offset at 52 and the side flanges 49 are shaped. One of these 50 projecting portions 55 is preferably arranged at each corner of the panel piece, preferably in the same plane as the offset portion 52 and are adapted to project through the slots or apertures 48 in the sections 46 when the parts are assembled and 55 then flanged or bent down against the inner face of the sides of the sections 46, as shown at 56 in Fig. 14. When the sections comprising the back are thus assembled and secured together the laterally deflected extremities 53 of the panel sections will stand in the same plane as the body portion of the sections 46. The back thus constructed 60 may be formed of any desired height preferably of a height equal to the height of the

sides of the refrigerator and the back is secured in position in the same manner in which the rear extremities of the sides are secured, that is, the edges of the interengaging flanges are adapted to be inserted in the kerfs 43 in the uprights 42 and the back 65 is held against accidental displacement by means of suitable fastening devices adapted to pass through suitable apertures 57 in the flange 53 and the extremities of the sections 46. Similar uprights 41 are adapted to be 70 arranged at the front corners of the refrigerator and the forward extremities of the sides 39 of the refrigerator may be secured thereto in the same manner in which the rear extremities are secured to the respective uprights 41. 75

Metallic corner pieces 58 are provided and are of substantially L-shaped configuration. The lower extremities of these corner pieces are deflected as at 59 to form inwardly projecting flanges and these corner pieces are adapted to be inserted in the castings 33 so that the sides of the corner pieces adjacent the bottom thereof will engage the sides of the casting and the flanges 59 will 80 rest upon the flange 37 on the casting 33 and these corner pieces may be held against displacement with respect to the castings 33 by means of the fastening devices 37^a which 85 pass through the apertures 38 in the flanges 37 and into the filler 31 of the base and which pass through apertures 60 in the flanges 59. These corner pieces 58 are 90 preferably of a height substantially equal to the height of the corner pieces 41, 42 and are 95 adapted to overlap the edges of the sides and backs where they engage and are secured to the uprights 41, 42, as shown more clearly in Fig. 4 of the drawings.

A suitable projection 61, such as a dowel 105 pin or the like, extends below the bottom of the uprights 41, 42 at each corner, (see Fig. 13) and this dowel or projection 61 is adapted to be inserted in registering apertures 62, 63 respectively in the flanges 37 110 of the casting 33 and the flange 59 of the corner pieces 58 so that the upright will be held at its lower extremity from displacement and the corner pieces may also be secured against displacement by means of 115 suitable fastening devices, such as bolts or rivets 64, (see Fig. 1) which pass through the corner pieces 58 and into the uprights, and fastening devices 65 which pass through the castings 33, corner pieces 58 and into the 120 uprights 41, 42. The rear corner of one of the uprights at each corner of the refrigerator, preferably the upright 41 is beveled or cut away for its entire length as at 66 for a purpose to be set forth, and the flange 125 37 on the corner piece 33 is provided with a threaded aperture 67 as shown more clearly in Fig. 5 of the drawings for a purpose to

be set forth. When the sides 39 are assembled and secured to the respective corner pieces, one of the flanges of the uppermost section 20 extends over and rests upon the 5 top edge of the respective uprights 41, 42.

With the parts of the refrigerator thus far assembled, and with the top constructed as already described, the latter is placed upon the top edges of the uprights 41, 42, 10 so as to rest upon the flange of the top sections of the sides and back, as shown more clearly in Figs. 10 and 13. The corners of the top are provided with apertures 68 which pass therethrough and are so arranged that when the top is in position the respective aperture therethrough will register with the space formed by the beveled edge 66 of the upright 41 and the corner of the angle pieces 58, as shown in Fig. 11 15 of the drawings. The top is preferably provided with countersunk portions 69 adjacent the apertures 68 for the reception of a suitable washer 70. Tie bolts or rods 71, provided with heads 72, are adapted to project through the washers 70, apertures 68, 20 through the space formed by the beveled edge 66 of the upright 41 and the free extremity 73 of the tie rod or bolt is provided with screw threads adapted to engage the 25 threads in the aperture 67 of the corner pieces 33 so that when the parts are assembled and the tie rods or bolts 71 placed in position, these bolts or rods will bind the 30 parts together, the countersunk portion 69 being adapted for the reception of the head of the bolt.

A cap 74 is provided with a peripheral flange 75 and this cap is adapted to be placed upon the top of the refrigerator so that the 40 side flanges 75 will overlap the edges of the top and rest against the outer faces of the walls of the refrigerator, as shown in Fig. 10, and this cap is provided with a suitable aperture 76 which registers with the countersunk portion 69 so that the tie rods or 45 bolts 71 may be removed to permit the parts to be separated. Suitable corner pieces or shields 77 may be provided for securing the cap 74 in position and for closing the aperture 76 in the cap over the head of the bolt 72 for sealing the latter.

The back may be provided with similar insulation 27 and an insulating strip or sheet of material 28 which may be secured 50 in position by means of fastening ears 50^a in the same manner that it is secured to the sides of the refrigerator.

In assembling the parts thus far, the insulation or packing 27 may be first placed 60 within the respective sections constituting the walls of the refrigerator before the walls are secured in position, or may be placed in the sections after the walls are in position and the extremities of the insulation 28

are adapted to be secured to the face of the 65 respective uprights 41, 42, after which a suitable lining 78, such as porcelain, slate, metal or the like, may be secured over the insulation 28 by means of its extremities being secured to the respective uprights 41, 70 42, in any suitable manner.

At the front of the refrigerator and adjacent each of the uprights 41 is an upright, preferably comprising two members 79, 80, one of which is preferably of a greater 75 width than the width of the other and these uprights extend for the entire height of the refrigerator to form an offset portion and these uprights may be insulated from each other by means of suitable insulation 81.

Arranged at the front of the refrigerator and between the uprights formed by these members 79, 80, is a frame comprising upright stiles designated generally by the reference numeral 82 in Fig. 1 and cross stiles 85 designated generally by the reference numerals 83, 84, in Fig. 1 of the drawings, and an intermediate cross stile designated generally by the reference numeral 89 in Fig. 1 to divide the opening formed by the frame into an upper and lower door opening. The upright stiles are constructed of metal and comprise a main body portion 86 (see Fig. 15) having a deflected portion 87 and an offset portion 88 arranged at substantially right angles to the portion 87 to form a shoulder, and a deflected portion 89 arranged in a plane inclined to the plane of the portion 87 to form a beveled edge around the frame, as shown in Fig. 4. The 100 portions 86 of the upright stiles are adapted to rest against the outer face of the respective member 80 and in substantially the same plane as the plane of the adjacent portion of the corner piece 58, as shown more 105 clearly in Fig. 4 of the drawings. A filler 90 preferably in the form of strips of wood are arranged between the outer edge of the members 80 and the offset portions 87 of the upright stiles, and a similar filler 91 110 is arranged between the outer edge of the filler 79 and the inclined portion 89 of the upright stile. The extremity of the inclined portion 89 of the stile is bent backwardly against the rear face of the filler 91, as 115 shown at 92 in Figs. 4 and 15 and a strip of material 93 is arranged between the edge of the deflected portion 92 and the adjacent face of the uprights 41, as shown more 120 clearly in Fig. 4. The upper and lower cross stiles 83, 84, are formed in a similar manner. The intermediate stile designated generally by the reference numeral 85 in Fig. 1 of the drawings is also constructed of metal and comprises a main body portion 125 94 (see Fig. 15) the edges of which are bent to form flanges 95 which project laterally from the body portion and are spaced

from each other a distance to produce a stile of the desired height. The ends of the flanges 94 are bent as at 96 and these portions 96 are located in a plane substantially parallel with the plane of the main body portion 94 to form shoulders, the faces of which are flush with the faces of the portions 88 on the upright stiles 86 and against which the edges of the doors abut. The portions 96 may be of any desired width and the edges thereof are bent to form inclined portions 97 and the extremities 98 of these portions are bent to form lips which are adapted to rest against the rear face of a filler block 99 which is inserted between the portions 98 and the shoulders 96. A similar filler block 100 is inserted in the space formed by the main body portion 94, the filler 99 and the flanges 95. This stile is of a length substantially equal to the width of the space between the upright stiles 82. This stile 85 is of the same construction as the stiles 83, 84, with the exception that the stiles 83, 84 are provided with shoulders 25 on the adjacent edges while the stile 85 is provided with shoulders 96 on both edges so that when the stile 85 is in position the shoulder 96 on the upper edge thereof will coöperate with the shoulder on the stile 83 to form an abutment for one door and the shoulder 96 on the lower edge of the stile 85 will coöperate with the shoulder on the stile 84 to form abutments for the other door of the refrigerator. These stiles may be secured to the upright stiles in any desired or suitable manner, preferably by extending the extremities 101 (see Fig. 15) of the body portion beyond the extremities of the respective fillers. The main body portion 40 94 and its filler 100 are of a greater length than the length of the shoulders 96, inclined portions 97 and the filler 99 so that when the cross stiles are placed in position between the upright stiles the main body portion 94 and its filler 100 will rest against the portion 88 of the upright stile while the extremities thereof will rest against the portions 87 of the upright stiles and the extremities of the filler 99, shoulders 96 and 50 inclined portions 97 will stand between the upright stiles and engage the faces of the inclined portions 89 of the stiles. The upright stiles are provided with suitable slots preferably at the edge formed between the main body portion of the upright stiles and the portion 87 thereof, and the projecting extremities 101 of the cross stiles are adapted to project through these respective slots to be crimped or folded over the portions 60 102 of the upright stiles which have been cut away to form the slot through which the extremities 101 pass and the joint thus formed between the upright stiles and the cross stiles hold the latter in position, as shown more clearly in Figs. 11 and 15 of 65 the drawings. A suitable strip of material 103 is secured to the rear face of the filler 99 between the extremities of the flanged portions 98 of the stile. The frame thus formed constitutes the front wall of the 70 refrigerator and comprises the upright stiles 82, the cross stiles 83, 84 and the intermediate cross stile 85 and is adapted to be constructed and placed into position so that a portion of the upright stiles 86 will project 75 over the uprights 80 at the front corners of the refrigerator and the frame is secured in position in any desired or suitable manner, preferably by means of suitable fastening devices 104 such as screws, bolts or the like, (see Fig. 1) which pass through the stiles 86 and the adjacent portions of the uprights 80. If desired, suitable packing or insulation 105 may be provided between the fillers 99, 100 of the stiles. 85

The doors or closures 106, 107 are both constructed in a similar manner with the exception that the lower door 107 is preferably of a larger size. The doors comprise a body portion 108 which is shaped to form 90 peripheral inclined flanges 109 of an inclination to correspond with the inclined portions 89, 97, of the respective door openings and beyond this inclined portion the flanges are offset as at 110 to correspond with the 95 shoulders or portions 88, 96 of the door openings, and the portions of the flanges beyond the offset portion 110 are bent as at 111 (see Fig. 4) to correspond with the portions 87, 93 of the door openings while the extremities 112 of the flanges are deflected laterally. The portion of the door thus formed may be filled with suitable packing or insulation 113 of a material similar to the packing or insulation 27, 28 in the walls, top and bottom 105 of the refrigerator and arranged within the body portion of the door are fillers 114 preferably constructed of wood which are located adjacent the portions 111 and the deflected portions 110 and serve to reinforce 110 the door as well as protect the deflected portions 110 from injury caused by the closing of the door or the portions 110 against the coöperating parts of the door openings. The face of the door is preferably constructed of 115 a single piece of material 115 of a size somewhat larger than the door and the edges 116 of this face extend beyond the edges of the deflected portions 112 of the body portion 108 and are adapted to be bent or flanged 120 around said portions 112, as shown more clearly in Fig. 4, for securing the face 115 of the door in position. The doors may be secured in position preferably by means of hinges 117 which are offset in the usual 125 manner, as shown more clearly in Fig. 4, and suitable fastening devices 118 may be provided for locking the doors closed. If de-

sired, suitable strips of packing material 118^a, such as felt or the like, may be secured to the edges of the doors to form tight joints. The interior of the refrigerator may be divided into any desired number of compartments and for this purpose there may be provided suitable brackets or supports 119 which may be secured in position in any desired or suitable manner. These brackets 10 are preferably located at the corners of the refrigerator and one set is arranged adjacent the top and supported thereby is a suitable shelf or partition 120 upon which rests a suitable tank or pan 121, which is of a size 15 somewhat less than the size of the refrigerator and the upper extremities 122 of the walls 123 are deflected outwardly beyond the walls to form flanges which are adapted to rest against the inner face of the walls of 20 the refrigerator to form air spaces 124 between the walls of the pan or tank and the wall of the refrigerator. The walls on one side are provided with apertures or openings 125 adjacent the bottom thereof while those 25 on the opposite side are provided with apertures 126 so that the warm air entering the tank 123 and contacting with the ice therein will pass out of the apertures 125 at the bottom of the tank as the temperature thereof lowers and will circulate to the bottom of the lower compartment and will then pass 30 into the air space 124 on the opposite side of the tank and through the apertures 126 at the top of the tank back into the tank. A 35 suitable rack 127 may be provided in the tank for supporting the ice above the bottom thereof. An outlet pipe 128 leads from the tank 121 and has communication with a discharge pipe 129 preferably located at the 40 rear of the refrigerator and this pipe 129 discharges into a suitable drip pan 130 which latter is provided with a suitable outlet 131. The pan 130 is located at the bottom and within the refrigerator and rests 45 upon the base formed by the sections 20 to form a closure or cover for the base. This pan is provided with a plurality of spaced partitions 132, which latter are provided with apertures 133 in the bottom thereof to 50 permit the water to pass therethrough. These partitions 132 are of a height equal to the height of the walls of the pan and a cap or closure 134 is provided for the pan and through which latter the extremity of the 55 discharge pipe 129 passes. The cap or closure 134 constitutes the bottom of the refrigerator upon which articles may be placed and the partitions 132 serve to support or reinforce the same. Arranged within 60 in the lower compartment formed between the pan 130 and the shelf 120 is another shelf or support 135 upon which the articles may be placed.

The base of the refrigerator is so arranged 65 as to be a short distance above the floor and

the space formed between the bottom of the refrigerator and the floor may be closed by panels 136 which are provided with flanges 137 at the extremities thereof and the panels are of such a length that the flanges 137 will extend between and stand adjacent the respective corner pieces 33. The flanges 137 extend from the bottom of the panels and terminate short of the top thereof, as shown more clearly in Fig. 2 of the drawings, so that when the panels are in position the portion of the plate above the upper edges of the flanges will stand adjacent the outer face of the refrigerator and the panels may be held in position by means of suitable fastening devices 138 which extend through the flanges 137, the base 34 of the corner pieces 33 and into the fillers 34^a. One of the panels at the bottom of the refrigerator is constructed to form a door or gate 139 and the extremities thereof are deflected to form flanges 140 which extend the entire width thereof. The gate 139 is of a length substantially equal to the distance between two of the uprights of the refrigerator and is supported by means of suitable hinges 141 secured to the lowermost panel of one of the walls of the refrigerator and when in position is adapted to be moved back and forth upon the hinges and the flanged extremities 140 will stand adjacent the respective corner pieces 33.

If desired, a suitable drain cock 142 may be provided which extends through one of the walls of the refrigerator and has communication with the pan 132.

With this improved construction of refrigerator it will be apparent that the various parts and sections may be all formed at one time and then shipped to the place of installation and erected by joining the various parts and sections in the manner set forth. It will also be apparent in so shaping and forming the various panels and sections, one set of dies may be used to construct a refrigerator of a large or small size, as the panels will be shaped by one set of dies and having been constructed of the desired length the extremities of the panels are successively inserted or placed between suitable cutting and shaping dies which stamp, perforate and bend the ends into the desired shapes. This is possible by the fact that the panels are all of the same height, the length only varying when it is desired to construct a refrigerator of a greater cross sectional area and the refrigerator may be built or constructed of any desired height by adding any suitable number of panels or sections thereto.

It is, of course, to be understood that suitable packing material may be provided at any desired point to cover or protect the joints between sections whenever it is found necessary and it is also to be understood that

if it is found necessary the flanges of the metallic sections may be provided with a suitable coating of white or red lead or any other suitable waterproofing material to 5 form air tight joints between these sections. With this improved construction it will also be apparent that the insulating material 27 for the walls of the refrigerator will be supported by the ribs formed by the abutting 10 flanges of the wall panel units, and by providing these spaced supports for the insulating material throughout the height of the wall, the insulating material will be prevented from settling or packing down in the 15 walls, which packing or settling would permit an air space to be formed in the walls at the top or above the insulating material. Furthermore it will be apparent that the front section is detachably secured in position 20 so that the entire front wall section may be removed as a unit.

In order that the invention might be fully understood the details of an embodiment thereof have been thus specifically described, 25 but

What I claim as new is:—

1. A sectional refrigerator including wall panels constructed of sheet material, each provided with laterally projecting 30 flanges, one of the flanges on one panel overlapping one of the flanges of the next adjacent panel, and means for securing the panels to each other to form unit members.

2. A sectional refrigerator including 35 metallic wall panels each provided with laterally projecting flanges, one of the flanges on one panel resting against and being flanged over one of the flanges of the next adjacent panel, and interengaging 40 means on the abutting flanges for securing the panels to each other to form unit members.

3. A refrigerator including metallic wall 45 panels each provided with laterally projecting flanges, one of the flanges of one panel resting against one of the flanges of the next adjacent panel, one of said abutting flanges being provided with an aperture and the other being provided with a cut out portion 50 to form a projecting ear adapted to pass through the said aperture to be bent against the face of the other flange for securing the panels together.

4. A refrigerator including metallic wall 55 panels, each provided with laterally projecting flanges, means for securing one of the flanges of one section to one of the flanges of another section to form a wall, and insulating material supported by the respective 60 panels intermediate the flanges thereof, a portion of the said insulating material extending over the abutting edges of the flanges.

5. A refrigerator including metallic wall 65 panels, each provided with laterally project-

ing flanges, means for securing one of the flanges of one section to one of the flanges of another section to form a wall, insulating material supported by the respective panels intermediate the flanges thereof, a portion 70 of the said insulating material extending over the abutting edges of the flanges, and means for securing the insulating material against displacement.

6. A refrigerator including walls provided with spaced inwardly projecting horizontally disposed ribs arranged throughout the length of the wall, and insulating material engaging and resting against the edges of the said ribs, a portion of the insulating material projecting into and filling the spaces between adjacent ribs. 75

7. A refrigerator including walls provided with spaced inwardly projecting horizontally disposed ribs arranged throughout 80 the length of the wall, and insulating material engaging and resting against the edges of the said ribs, a portion of the insulating material projecting into and filling the spaces between adjacent ribs, said ribs 85 being provided with projecting ears adapted to penetrate the insulating material for securing the latter against displacement.

8. A refrigerator including walls constructed of a plurality of units, each of said 90 units being provided with laterally projecting flanges, one of the flanges of one section extending beyond and being bent over the edge of the adjacent flange of the next unit, and being provided with a cut out portion 100 adjacent the edge of the rib formed by the abutting flanges, and insulating material engaging and resting against the edges of the ribs, said cut out portion passing through the insulating material and being 105 bent down upon the material to secure the latter in position, a portion of the insulating material extending into the spaces formed between the said ribs.

9. A wall panel unit for refrigerators 110 constructed of sheet material and comprising a body portion, provided with laterally projecting flanges at the sides thereof, one of the flanges being bent back upon itself to form an open overhanging portion adjacent 115 its free edge, said flange being provided with a lug adjacent the bend in the flange and projecting beyond the edge formed by the bend, insulating material through which the lug projects, one of the flanges being provided with a projecting portion extending laterally beyond the flange and the other flange being provided with corresponding apertures at a point remote from the free edge of the flange. 120

10. A metallic unit panel for refrigerators comprising a body portion provided with laterally projecting flanges at the sides thereof, one of the flanges being bent back upon itself to form an open overhanging 125

- portion adjacent its free edge, the said bend being provided with a cut out portion adjacent and bent to project beyond the edge formed by the bend, one of the flanges being also provided with a cut out portion remote from the free edge thereof and bent to project laterally beyond the flange the other flange having corresponding apertures. 70
11. A metallic refrigerator including walls comprising a plurality of unit wall panels secured together, a top, a bottom, said top and bottom each including a plurality of unit panels secured together, insulating material supported by the said unit panels means for securing the walls of the refrigerator in position and fastening means for the insulating material. 75
12. A metallic refrigerator including a top, a bottom, said top and bottom each comprising a plurality of unit panels, means for securing the panels together, a supporting frame for the panels surrounding the periphery of the assembled panels, a filler disposed between the respective frame and the peripheral edge of the panel sections, insulating material supported by the said sections, a cover for the insulating material, and means for securing the parts in an assembled position. 80
13. A refrigerator constructed of sheet material and including a top, and bottom, and a back and side walls, all of said parts being sectional in construction and each comprising a plurality of unit panels secured together, a sectional front for the refrigerator, said front comprising spaced upright stiles and transverse stiles separate from and connecting the upright stiles to form door openings, means for removably securing the parts in an assembled position, and closures for the said door openings. 85
14. A metallic refrigerator including a top and bottom and a back and side walls, each of said parts comprising a plurality of unit panels secured together, uprights, means for securing the extremities of the walls to the uprights, said uprights forming corner posts for the refrigerator, a sectional front for the refrigerator, said front comprising spaced upright stiles, and transverse stiles removably secured to the upright stiles to form door openings, filler members for the stiles, the filler members of the upright stiles being disposed adjacent the uprights at the front of the refrigerator, metallic corner pieces inclosing and extending for substantially the length of the said uprights, means for securing the parts in their assembled position, and closures for the door openings. 90
15. A metallic refrigerator including walls comprising unit panel members, each of which is provided with laterally projecting flanges, inter-engaging means on the flanges for securing one of the flanges of one unit to one of the flanges of the adjacent unit to form laterally projecting ribs, and corner uprights for the said walls, said uprights being provided with recesses into which the free edges of the said ribs are adapted to project. 95
16. A metallic refrigerator including walls comprising unit panel members, each of which is provided with laterally projecting flanges, means for securing one of the flanges of one unit to one of the flanges of the next adjacent unit to form laterally projecting ribs, and uprights for the said walls, said uprights being provided with recesses into which the free edges of the ribs are adapted to project, whereby the body portion of the unit will engage the face of the respective upright, the body portion of one of the units being disposed in a plane beyond the plane of another section to form an offset panel, the extremities of said offset unit being bent to form flanges disposed in substantially the same plane as the body portion of the next adjacent unit and adapted to engage the face of the said upright. 100
17. A metallic refrigerator including corner pieces, each of said corner pieces being provided with spaced parallel laterally projecting flanges, a base member, the corners of said member being adapted to engage the corner pieces between the said flanges, sectional walls supported by the base member, corner posts to which the walls are secured, a metallic corner member inclosing the corner posts, the lower extremities of said member and the posts engaging the respective corner pieces and resting upon one of the flanges thereof, means for preventing lateral displacement of the corner posts and said pieces, a top supported by the corner posts, and means passing through the top at the corners thereof and engaging the respective corner pieces for holding the parts assembled. 105
18. A metallic refrigerator including corner pieces, each of said corner pieces being provided with spaced parallel laterally projecting flanges, a base member, the corners of said member being adapted to engage the corner pieces between the said flanges, sectional walls supported by the base member, corner posts to which the walls are secured, a metallic corner member inclosing the corner posts, a portion of said posts being cut away to form a space between said posts and the inclosing member, the lower extremities of said member and the posts engaging the respective corner pieces and resting upon one of the flanges thereof, means for preventing lateral displacement of the corner posts and said pieces, a top supported by the corner posts, and tie rods passing through the top at the corners thereof and the said spaces and detachably engaging the respective corner pieces for holding the parts assembled. 110
19. A metallic refrigerator including corner pieces, each of said corner pieces being provided with spaced parallel laterally projecting flanges, a base member, the corners of said member being adapted to engage the corner pieces between the said flanges, sectional walls supported by the base member, corner posts to which the walls are secured, a metallic corner member inclosing the corner posts, a portion of said posts being cut away to form a space between said posts and the inclosing member, the lower extremities of said member and the posts engaging the respective corner pieces and resting upon one of the flanges thereof, means for preventing lateral displacement of the corner posts and said pieces, a top supported by the corner posts, and tie rods passing through the top at the corners thereof and the said spaces and detachably engaging the respective corner pieces for holding the parts assembled. 115
20. A metallic refrigerator including corner pieces, each of said corner pieces being provided with spaced parallel laterally projecting flanges, a base member, the corners of said member being adapted to engage the corner pieces between the said flanges, sectional walls supported by the base member, corner posts to which the walls are secured, a metallic corner member inclosing the corner posts, a portion of said posts being cut away to form a space between said posts and the inclosing member, the lower extremities of said member and the posts engaging the respective corner pieces and resting upon one of the flanges thereof, means for preventing lateral displacement of the corner posts and said pieces, a top supported by the corner posts, and tie rods passing through the top at the corners thereof and the said spaces and detachably engaging the respective corner pieces for holding the parts assembled. 120
21. A metallic refrigerator including corner pieces, each of said corner pieces being provided with spaced parallel laterally projecting flanges, a base member, the corners of said member being adapted to engage the corner pieces between the said flanges, sectional walls supported by the base member, corner posts to which the walls are secured, a metallic corner member inclosing the corner posts, a portion of said posts being cut away to form a space between said posts and the inclosing member, the lower extremities of said member and the posts engaging the respective corner pieces and resting upon one of the flanges thereof, means for preventing lateral displacement of the corner posts and said pieces, a top supported by the corner posts, and tie rods passing through the top at the corners thereof and the said spaces and detachably engaging the respective corner pieces for holding the parts assembled. 125
22. A metallic refrigerator including corner pieces, each of said corner pieces being provided with spaced parallel laterally projecting flanges, a base member, the corners of said member being adapted to engage the corner pieces between the said flanges, sectional walls supported by the base member, corner posts to which the walls are secured, a metallic corner member inclosing the corner posts, a portion of said posts being cut away to form a space between said posts and the inclosing member, the lower extremities of said member and the posts engaging the respective corner pieces and resting upon one of the flanges thereof, means for preventing lateral displacement of the corner posts and said pieces, a top supported by the corner posts, and tie rods passing through the top at the corners thereof and the said spaces and detachably engaging the respective corner pieces for holding the parts assembled. 130

19. A refrigerator constructed of sheet material and including corner pieces, each of said pieces being provided with spaced parallel laterally projecting flanges, a base member, the corners of said member being adapted to engage the corner pieces between the said flanges, sectional walls supported by the base member, corner posts for supporting the walls, a metallic corner member inclosing each of the corner posts, the lower extremities of the said member and the corner posts engaging and resting upon one of the said flanges, said flange being provided with a threaded aperture, a portion of the post being cut away to form a space between the post and the said inclosing member in line with the said threaded aperture, a top supported by the corner posts and a tie rod passing through each of the corners of the top and the adjacent space and having a threaded extremity engaging the threaded apertures in the said flanges for removably holding the parts assembled. 5 70
20. A metallic refrigerator including corner pieces, each of said pieces being provided with spaced parallel laterally projecting flanges, a base member, the corners of said member being adapted to engage the corner pieces between the said flanges, sectional walls supported by the base member, corner posts for supporting the walls, a metallic corner member inclosing each of the corner posts, the lower extremity of the said member being flanged inwardly and adapted 10 75
- 35 to rest upon one of the flanges of the respective corner piece, said flanges being provided with registering apertures, the lower extremity of the post being provided with a projection adapted to enter the registering apertures to hold the parts against lateral displacement, a top supported by the corner posts and means engaging the top and the corner pieces for holding the parts detachably assembled. 40 80
- 45 21. A metallic refrigerator including corner pieces, each of said pieces being provided with spaced parallel laterally projecting flanges, a base member, the corners of said member being adapted to engage the corner pieces between the said flanges, sectional walls supported by the base member, corner posts for supporting the walls, a metallic corner member inclosing each of the corner posts, the lower extremity of said member 50 85
- 55 being provided with a flange adapted to rest upon the flange of the respective corner piece, said flanges being provided with registering apertures, the lower extremity of the post being provided with a projection adapted to enter the said registering apertures to hold the parts against lateral displacement, said corner pieces being also provided with a threaded aperture, a top supported by the posts, and tie rods extending through the top 60 90
- 65 at each corner thereof and having a threaded extremity adapted to engage the threaded aperture in the respective corner pieces for holding the parts detachably assembled. 95
22. A top and bottom member for metallic refrigerators, each comprising a body formed of a plurality of unit panels, said units being secured one to the other, a frame adapted to receive the body thus formed and to surround only the peripheral edge thereof, and means for holding the body against displacement. 100 105
23. A top and bottom member for metallic refrigerators, each comprising a body formed of a plurality of unit panels, said units being secured one to the other, a frame adapted to receive the body thus formed and to surround only the peripheral edge thereof, said body being of a size somewhat smaller than the frame, a filler disposed between the frame and the peripheral edge of the body, and means for preventing displacement of the parts. 110 115
24. A top and bottom member for metallic refrigerators, each comprising a body formed of a plurality of unit panels, said units being secured one to the other, a frame adapted to receive the body thus formed and surround only the peripheral edge thereof, said frame being provided with flanges adapted to overlap the top and bottom edges of the body, and means for securing the parts against displacement. 120 125
25. A top and bottom member for metallic refrigerators, each comprising a body formed of a plurality of unit panels, said units being secured one to the other, a frame adapted to receive the body thus formed and surround only the peripheral edge thereof, said frame being provided with flanges adapted to overlap the top and bottom edge of the body, filler members disposed between the respective edges of the body and the walls of the frame, and means for securing the parts against displacement. 130

28. A top and bottom member for metallic refrigerators, each comprising a body formed of a plurality of unit panels secured together, said body being provided with 5 spaced projecting flanges, a frame for receiving the edges of the body thus formed, insulating material supported by the flanges and projecting into the space formed between the flanges, and fastening means for 10 the insulating material for preventing displacement thereof.

29. A sectional refrigerator including independent wall panels constructed of sheet material, one edge of one panel being disposed adjacent one edge of the next adjacent panel, and means integral with the panel for locking the panels one to the other and against detachment with respect to each other.

20 30. A sectional refrigerator including independent wall panels constructed of sheet material, one edge of one panel being disposed adjacent one edge of the next adjacent panel, and inter-locking means on the panels 25 for locking the panels one to the other and against detachment with respect to each other.

31. A sectional refrigerator including independent wall panels constructed of sheet 30 material, one edge of one panel being disposed adjacent one edge of the next panel, interengaging means on the panels for securing the panels to each other, insulating material adjacent the panels, and means integral with the panels for securing the insulating material in position.

32. A sectional refrigerator including independent wall panels constructed of sheet material, one edge of one panel being disposed adjacent one edge of the next panel, interengaging means on the panels for securing the panels to each other, insulating material adjacent the panels, and means integral with the panels and adapted to penetrate the insulating material for holding the latter in position.

33. A sectional refrigerator including a back and side walls, each comprising a plurality of wall panels, each panel being constructed of sheet material and secured one to the other and against detachment with respect to each other, a front wall section comprising a frame provided with a door opening, a closure for the opening, and means for 50 securing the said front wall section in position whereby the latter may be removed as a unit.

34. A refrigerator including a back and side walls, each constructed of a plurality of 30 wall panels and each panel constructed of sheet material, interengaging means on the panels for securing one panel to the next adjacent panel against detachment with respect to each other to form unit members, a front wall section provided with a door.

opening and comprising a frame constructed of sections of sheet material secured together, a closure for the opening, and means for securing the said front wall section in position whereby the wall section may be 70 removed as a unit.

35. A sectional refrigerator including a back and side walls, each comprising a plurality of wall panels, each panel being constructed of sheet material and secured one to 75 the other and against detachment with respect to each other, a front wall section comprising a frame provided with a door opening, a closure for the opening, means for securing the said front wall section in 80 position whereby the latter may be removed as a unit, insulation adjacent the walls, and means integral with the walls and adapted to penetrate the insulation to hold the latter in position.

36. A metallic refrigerator including walls comprising unit panel members each of which is provided with laterally projecting flanges, fastening devices for securing one of the flanges of one unit to one of the flanges of the adjacent unit to form laterally projecting ribs, and corner uprights for said walls, said uprights being provided with recesses into which the free edges of the said 90 ribs are adapted to project.

37. A refrigerator comprising a casing having a top, said top being sectional in construction separate from the casing and removable therefrom, the periphery of the top coinciding with the outer faces of the walls 100 of the casing, and a cap inclosing the top, said cap having a depending peripheral flange projecting over the edge of the adjacent portion of the surrounding wall of the casing.

38. A refrigerator comprising a casing having a top, said top being sectional in construction separate from the casing and removable therefrom, the periphery of the top coinciding with the outer faces of the walls 110 of the casing, and a cap inclosing the top, said cap being constructed of sheet material and having a depending integral peripheral flange projecting over the edge of the adjacent portion of the wall of the casing.

39. A refrigerator comprising a casing having a top, said top being sectional in construction separate from the casing and removable therefrom, the periphery of the top coinciding with the outer faces of the walls 120 of the casing, and a cap inclosing the top, said cap having a depending peripheral flange projecting over the edge of the adjacent portion of the surrounding wall of the casing and means for detachably securing 125 the cap in place.

40. A refrigerator comprising a base, side walls, and a top with its periphery coinciding with the outer faces of the walls of the casing, said top being sectional in construction 130

tion, removably supported by the walls, a cap resting upon and covering the top, said cap being provided with a peripheral flange inclosing the edges of the top and extending beyond the top and resting against the outer faces of the adjacent portions of the walls.

In testimony whereof I have signed my

name to this specification, in the presence of two subscribing witnesses, on this 28th day of April, A. D. 1908.
